Samuel Richards

United States Patent Office.

SAMUEL RICHARDS, OF PHILADELPHIA, PENNSYLVANIA.

Letters Patent No. 65,605, dated June 11, 1867.

IMPROVED SNOW-PLough.

The Schedule referred to in these Letters Patent and making part of the same.

TO ALL WHOM IT MAY CONCERN:

Be it known that I, SAMUEL RICHARDS, of Philadelphia, State of Pennsylvania, have invented a new and useful improvement in Snow-Ploughs; and I do hereby declare the following to be a full and exact description thereof, reference being had to the annexed drawings, making a part of this specification, in which—

Figure 1 is a horizontal section of my improvement.

Figure 2 is a vertical section; and

Figure 3 is a perspective view of the same.

The present invention is an improvement on my former plough, and consists in constructing an inclined plane, A A', open at the sides, of a length of about twenty to thirty feet, mounted upon two sets of swivelling trucks, as heretofore patented by me, and placing thereon a bridge-piece, B, the pivot thereof being located high enough to be above the level of the surrounding snow, say about eight feet above the track. This bridge-piece B is pivoted to the plane at its rear or large end at e, so that it can occupy a central position, or at either side. The block D is vibrated by an endless chain, g, on a windlass, h. At the lower extremity of this movable wedge is an auxiliary hinged flap, c, attached to the point of said wedge and moving with it, and so that it can be turned about the hinge f, by which it is pivoted to the point of the wedge. This flap piece c should be of the same height from the plane as the wedge, and about six to eight feet in length. Its object is to prevent the snow from spilling over on to the adjoining track.

Having thus described my improvement, what I claim as my invention, is—

The combination of the inclined plane A A', and the movable wedge-block B, and the pivoted flap c, arranged and operating substantially as described.

SAMUEL RICHARDS.
